(57) **CLAIM**

The ornamental design for a golf ball hole size selector putting aid as shown and described.

DESCRIPTION

FIG. 1 is a top perspective view of the golf ball hole size selector putting aid of the instant invention;
FIG. 2 is a bottom perspective view thereof;
FIG. 3 is a front side view thereof;
FIG. 4 is a left side view thereof;
FIG. 5 is a bottom view thereof;
FIG. 6 is a top view thereof;
FIG. 7 is a right side view thereof; and
FIG. 8 is a back view thereof; and
FIG. 9 is a top perspective environmental view thereof.
The broken lines represent environmental subject matter and
form no part of the claimed design.

1 Claim, 8 Drawing Sheets
